UNITED STATES PATENT OFFICE.

CHARLES H. HESS, OF ZANESVILLE, OHIO, ASSIGNOR TO THE KEARNS-GORSUCH BOTTLE COMPANY, OF SAME PLACE.

DESIGN FOR A BOTTLE.

SPECIFICATION forming part of Design No. 34,956, dated August 20, 1901.

Application filed July 26, 1901. Serial No. 69,854. Term of patent 7 years.

To all whom it may concern:

Be it known that I, CHARLES H. HESS, a citizen of the United States, residing at Zanesville, in the county of Muskingum and State 5 of Ohio, have invented and produced a new and original Design for a Bottle, of which the following is a specification.

The present invention relates to bottles; and the object thereof is to provide a design 10 of this character that is new, original, and ornamental.

The leading feature of the present design resides in a triangular body having the adjoining edges of its three side faces joined by 15 convexed portions that curve uniformly from one side to the other, the upper end of the side walls curving gradually to form a substantially circular breast, from which projects a centrally-disposed contracted neck. The 20 neck is provided with an annular bead, beneath which is located an annular series of ribs or flutes that extend longitudinally of the neck. The body of the bottle is also provided with an annular series of ribs or flutes, 25 which are located contiguous to its lower end and are arranged longitudinally of said body.

In the drawings which accompany and form a part of this specification, Figure 1 is a perspective view of a bottle embodying the present design. Fig. 2 is a horizontal sectional view through the same.

The body of the bottle shown in said drawings is substantially triangular in cross-section, as clearly shown in Fig. 2, the adjoining edges of the three side faces 10 being joined by convexed portions 11, that curve uniformly from one side to the other. The upper ends of the side walls curve gradually to form a substantially circular breast 12, from which projects a centrally-disposed contracted neck 40 35 13, having an annular bead, as 14. Beneath this bead there is located an annular series of ribs or flutes 15, that extend longitudinally of the neck, and another series of ribs or flutes 16 is located around the bottle contiguous to its lower end, said ribs or flutes being disposed longitudinally of the body. 45

Having thus described the invention, what I claim as new, and desire to secure by Letters Patent, is—

The design for a bottle as herein shown and described.

In testimony that I claim the foregoing as my own I have hereto affixed my signature in the presence of two witnesses.

CHARLES H. HESS.
